His attorney.

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 27, 1923. Serial No. 659,506.

My invention relates to railway traffic controlling apparatus, and particularly to automatic train control apparatus of the type comprising train carried governing mechanism controlled by energy received from the trackway. More specifically my invention relates to the trackway portion of such apparatus.

I will describe several forms of apparatus embodying my invention, and will then point out the novel features thereof in claims.

In the accompanying drawing, Fig. 1 is a diagrammatic view showing one form of trackway apparatus embodying my invention. Fig. 2 is a fragmental view showing a modification of one portion of the apparatus shown in Fig. 1 and also embodying my invention. Fig. 3 is a diagrammatic view, similar to Fig. 1, but showing a modified form of apparatus embodying my invention.

Similar reference characters refer to similar parts in each of the several views.

Referring first to Fig. 1, the reference characters 2 and 2^a designate the track rails of a railway, the rail 2^a being divided by insulated joints 3 to form track sections of which only one section, A—B, is shown in the drawing. Connected across the rails at one end of the section A—B is a source of alternating track circuit current, which, as here shown, is the secondary of a transformer 4, the primary of which is connected with a transmission line 6. Alternating current is constantly supplied to the transmission line by a generator 7. Preferably a resistance 8 is interposed between the secondary of transformer 4 and the track rail 2^a. Located adjacent the other end of the section A—B is a track relay R, which, as herein shown, is of the induction motor type, comprising two stator windings 11 and 12, a rotor 10, and a contact 13 controlled by the rotor. Stator winding 11 is constantly supplied with alternating current from the transmission line 6, while stator winding 12 is supplied with energy from the track rails of section A—B through the medium of a transformer T having a primary 15 connected across the rails and a secondary 16 connected with winding 12. It follows that relay R is operated by track

circuit current supplied to the rails of section A—B by transformer 4.

The track section A—B is also supplied with a local alternating train controlling current which is furnished by a transformer 5, the primary of which is connected with the transmission line 6. In the form shown in Fig. 1 the two terminals of the secondary of transformer 5 are connected with the divided rail 2^a at opposite ends of the section A—B, so that normally the local current flows in the divided rail 2^a only. A reactor 9 is interposed between one terminal of transformer 5 and rail 2^a.

It is understood that the trackway apparatus shown in Fig. 1 is intended for co-operation with train carried apparatus which is controlled jointly by the track circuit current from transformer 4 and by the local current from transformer 5. It is also understood that in practice the supply of local current from transformer 5 to the section A—B will be controlled by traffic conditions in advance of this section. The train carried apparatus, and the means for controlling the supply of local current, form no part, however, of my present invention, and, consequently, they are eliminated from the drawing for the purpose of simplicity.

When the apparatus shown in Fig. 1 is in normal condition it will be clear that there is no appreciable difference of potential of local current from transformer 5 across the rails 2 and 2^a, and so this local current cannot affect the track relay R. When a train W occupies the section A—B, however, if the divided rail 2^a should be broken at a point such as 21 between the train and the point B, current from the local transformer 5 may flow through wire 20, primary 15 of transformer T, rail 2, and then through the wheels and axles of the train W to rail 2^a and back to transformer 5. The presence of this local current in the primary of transformer T will, of course, produce an induced current in the secondary 16 and so in stator winding 12 of relay R. The parts may be so designed that the magnitude of the induced current is not sufficient to operate the relay R, so that even in the event of a train and a broken rail in section A—B, a dangerous condition would not be created. Certain re-

lays which are suitable for track relay purposes will respond, however, to the minimum value of local current which can be used for automatic train control, and when a relay 5 of this character is employed it would be necessary to depend upon phase relations of the currents in the stator windings 11 and 12 to prevent false operation of the relay by the local current. These relations are not 10 dependable as a safety factor, however, and, consequently, it is desirable to prevent such false operation in other ways. As shown in Fig. 1, I accomplish this result by 15 providing the core 14 of transformer T with an air gap 17, so that this transformer is of the open magnetic circuit type. The transformer T consequently produces the effect of an impedance in multiple with winding 12 of relay R and so it serves as a shunt 20 which prevents sufficient local current from reaching this winding to operate the relay. The source of track circuit current, however, is of such value as to pass through the transformer T in sufficient quantity to 25 operate the relay R.

The apparatus shown in Fig. 1 is particularly well adapted for use on electric railroads of the single rail return type, in which case the track rail 2 serves as the return for 30 the propulsion current.

Referring now to Fig. 2, the transformer between the track rails and the track relay R, which transformer is here designated T^A , is provided with a closed conductor 18 surrounding a portion of the magnetic circuit, such conductor preferably being of resistance material. A transformer of this character produces the effect of resistance in multiple with the relay winding 12, and this 35 effect may be more desirable in some combinations of relays and track circuits than the effect of an impedance in multiple with the relay winding. The function of the transformer T^A in Fig. 2 is the same, however, as the transformer T in Fig. 1, in that 40 it serves to shunt from the relay winding 12 such a quantity of the local current that the induced current cannot reach the relay winding in sufficient amount to operate the relay.

Referring now to Fig. 3, the apparatus shown in this view is the same as that shown in Fig. 1, except as to the means for supplying local current to the track rails. In Fig. 3 a resistance 19 is connected across the 55 track rails adjacent one end of the section A-B and a similar resistance 19^A is connected across the track rails adjacent the other end of the section. The two terminals of the secondary of local transformer 5 are connected with the middle points of these 60 two resistances 19 and 19^A respectively, so that the local current flows through the two rails 2 and 2^A in multiple. Normally this local current will be balanced in the two 65 rails, so that it will not produce a difference

of potential across the primary 15 of transformer T and so it will not influence the track relay R. In the event of sufficient unbalancing of the resistance of the two rails 2 and 2^A , however, such as may be caused by 70 a broken rail, local current may flow in the primary of transformer T, and so in the stator winding 12 of relay R. The air gap 17 in the core of transformer T causes this transformer to act as a reactance in multiple 75 with relay R, however, and so prevents local current from reaching relay R in sufficient quantity to operate this relay. As in Fig. 1, the track circuit current is of such magnitude as to pass through the transformer T in 80 sufficient quantity to operate the relay.

Obviously the transformer T^A shown in Fig. 2 may be substituted for the transformer T in Fig. 3, thereby producing the effect of a resistance instead of a reactance 85 in multiple with winding 12.

The apparatus shown in Fig. 3 is particularly well adapted for steam railroads, and for electric railroads in which both track rails are included in the circuit for the propulsion current. In either case both rails 90 2 and 2^A are divided by insulated joints 3 to form track sections.

One important feature of my invention is that it permits the use of a relay which will 95 respond to a smaller amount of track circuit current than could otherwise be employed. The invention is particularly well adapted for the application of train control apparatus to existing railway signaling systems, which systems comprise relays so designed that they would be falsely operated by a sufficient unbalancing of the local current. By means of my invention it is not necessary to change the relays in such a system.

While the transformers T and T^A produce the effects of a reactance and a resistance, respectively, in multiple with the relay winding 12, it will be noted that if either the primary or the secondary circuit of these transformers should be opened or broken, the relay will be de-energized, and, consequently, the failure will be on the safe side. On the other hand, if a small reactance or resistance were connected in multiple with the relay winding 12, a break in such reactance or resistance would not create a failure on the safe side, but, on the contrary, would result in a false energization of the relay in the event of sufficient unbalancing of the local current.

Where in the accompanying claims I have used the expression "impedance in multiple with the relay", I mean either the effect of a reactance produced by transformer T or 115 a resistance produced by transformer T^A .

Although I have herein shown and described only three forms of apparatus embodying my invention, it is understood that various changes and modifications may be 120 130

made therein within the scope of the appended claims without departing from the spirit and scope of my invention.

Having thus described my invention,

5 what I claim is:

1. Trackway apparatus for an automatic train control system on a railway of which one track rail is divided to form track sections, comprising a source of alternating track 10 circuit current connected across the rails of a section, a track relay operated by track circuit energy received from the rails of said section, a source of alternating local current connected with two points in the divided rail 15 of said section and capable under abnormal conditions of causing operation of said track relay, and a transformer interposed between said track rails and said track relay and having an air gap in its magnetic circuit and serving to prevent operation of said track relay by said local current under abnormal conditions.

2. Trackway apparatus for an automatic train control system on a railway of which one track rail is divided to form track sections, comprising a source of alternating track circuit current connected across the rails of a section, a track relay operated by track circuit energy received from the rails 25 of said section, a source of alternating local current connected with two points in the divided rail of said section and capable under abnormal conditions of causing operation of said track relay, and means interposed between said track rails and said track relay producing the effect of a reactor in multiple with the relay and thus preventing operation of said track relay by said local current under abnormal conditions.

40 3. Trackway apparatus for an automatic train control system on a railway of which one track rail is divided to form track sections, comprising a source of alternating track circuit current connected across the rails of a section, a track relay operated by track circuit energy received from the rails of said section, a source of alternating local current connected with two points in the divided rail of said section and capable under 45 abnormal conditions of causing operation of said track relay, and means interposed between said track rails and said track relay producing the effect of an impedance in multiple with the relay and thus preventing operation of said track relay by said local current under abnormal conditions.

45 4. Trackway apparatus for an automatic train control system on a railway of which one track rail is divided to form track sections, comprising a source of alternating track circuit current connected across the rails of a section, a track relay operated by track circuit energy received from the rails of said section, a source of alternating local 50 current connected with two points in the di-

vided rail of said section, and means interposed between said track rails and said track relay for preventing false operation of said relay by current from said local source.

5. Trackway apparatus for an automatic 70 train control system, comprising a section of track, a source of alternating track circuit current connected across the rails of said section, a track relay operated by track circuit energy received from the rails of 75 said section, a source of alternating local current for said section having the same frequency as said track circuit current and having a value sufficient to falsely operate said track relay, and means interposed between said rails and said relay for preventing local current from reaching the relay in sufficient quantity to operate the relay, said source of track circuit current being of such 80 value as to pass through said means in sufficient quantity to operate the relay.

6. Trackway apparatus for an automatic 85 train control system, comprising a section of track, a source of alternating track circuit current connected across the rails of 90 said section, a track relay operated by track circuit energy received from the rails of said section, a source of alternating local current for said section having the same frequency as said track circuit current and having 95 a value sufficient to falsely operate said track relay, and an open magnetic circuit transformer interposed between said rails and said relay for preventing sufficient local current from reaching the relay to operate the 100 relay, said source of track circuit current being of such value as to pass through said transformer in sufficient quantity to operate the relay.

7. Trackway apparatus for an automatic 105 train control system, comprising a section of track, a source of alternating track circuit current connected across the rails of said section, a track relay operated by track circuit energy received from the 110 rails of said section, a source of alternating local current for said section having the same frequency as said track circuit current and having a value sufficient to falsely operate said track relay, and a transformer interposed between said rails and said relay and provided with means for producing the effect of an impedance in multiple with the relay whereby the transformer 115 serves to prevent said local current from reaching the relay in sufficient quantity to operate the relay, said source of track circuit current being of such value as to pass through said transformer in sufficient quantity to operate the relay.

8. Trackway apparatus for an automatic 125 train control system, comprising a section of track, a source of alternating track circuit current connected across the rails of said section, a track relay operated by track 130

circuit energy received from the rails of said section, means for supplying alternating local current of the same frequency as said track circuit current to the two rails of said section in multiple, and means interposed between said rails and said relay for preventing local current from reaching the relay in sufficient quantity to operate the relay, said source of track circuit current being of such value as to pass through said last mentioned means in sufficient quantity to operate the relay.

9. Trackway apparatus for an automatic train control system, comprising a section of track, a source of alternating track circuit current connected across the rails of

said section, a track relay operated by track circuit energy received from the rails of said section, means for supplying alternating local current to the two rails of said section in multiple, and a transformer interposed between said rails and said relay and so designed as to produce the effect of an impedance in multiple with the relay whereby the transformer serves to prevent said local current from reaching the relay in sufficient quantity to operate the relay, said source of track circuit current being of such value as to pass through said transformer in sufficient quantity to operate the relay.

In testimony whereof I affix my signature.

SAMUEL M. LUCAS.
